UNITED STATES PATENT OFFICE.

JEREMIAH BINGHAM, OF TOLEDO, OHIO, ASSIGNOR TO THE TOLEDO MACHINE AND TOOL COMPANY, OF TOLEDO, OHIO, A CORPORATION OF OHIO.

DUPLEX EDGE-FOLDING AND SEAM-CLOSING MACHINE.

No. 850,614.

Specification of Letters Patent.

Patented April 16, 1907.

Application filed June 4, 1906. Serial No. 320,029.

To all whom it may concern:

Be it known that I, JEREMIAH BINGHAM, a citizen of the United States, and a resident of Toledo, in the county of Lucas and State of Ohio, have invented a certain new and useful Improved Duplex Edge-Folding and Seam-Closing Machine; and I do hereby declare the following to be a full, clear, and exact description of the invention, such as will enable others skilled in the art to which it appertains to make and use the same, reference being had to the accompanying drawings, and to the figures and letters of reference marked thereon, which form a part of this specification.

My invention relates to duplex edge-folding and seam-closing, bumping, or finishing attachments for power-presses or the like and which are commonly designated as "seaming horns and forces."

An object of my invention is to improve upon machines of this kind, whereby to increase their efficiency and practicability and enhance their commercial value.

A further object of my invention is the provision, in combination with an attachment of this class, of gage means for the work, which means is adjustable to increase or diminish the width of the terminal fold and also to provide a tapering folded edge and seam, which is desirable for certain kinds of work, thus making it possible to have the fold or seam start from wide to narrow, or vice versa, from either end.

The invention is fully described in the following specification and illustrated in the accompanying drawings, in which—

Figure 1 is a side elevation of a press equipped with my improved edge-folding and seam-closing attachment, with a portion of the press-frame broken away. Fig 2 is an enlarged front view of a portion of the slide or operating-head and the horn carrying the edge-folding means, the same being in normal or inoperative position. Fig. 3 is a side elevation of the parts shown in Fig. 2. Fig. 4 is a vertical cross-section of the operating-head and horn, with the latter shown partially in section on the lines $x-x$ and $x'-x'$ in Fig. 3. Fig. 5 is a central vertical longitudinal section of said parts. Fig. 6 is a cross-section of a portion of the edge-folding head, showing the swinging blade and the

compression-spring by which it is normally held in one position. Fig. 7 is a partial perspective view of the horn in cross-section, illustrating the gage-adjusting means with the screw-retaining plate removed. Fig. 8 is a front elevation of the invention, illustrating a modified arrangement of the parts; and Figs. 9 and 10 illustrate the edges of the work from the initial to the final stages of the operation in the formation of an outer and inner seam, respectively.

Referring to the drawings, 1 indicates the frame of a power-press of any suitable construction, and 2 the plunger or operating-head thereof, which carries the pressure-foot 3 at its lower end.

Mounted below the pressure-foot 3 is a horn 4, which is secured to the frame 1 by an arm or shank 5, projecting from its inner end and being secured within an opening provided therefor in the frame. Interposed between this horn and the pressure-foot 3 is a movable head 6, which extends the length of the horn and is normally spaced therefrom by the interposed strip 7, by which it is carried. This strip has its lower edge mounted within a suitable groove in the upper surface of the horn 4 and is fixed thereto by screws 8 and has its upper edge operating within an alining groove 9, provided longitudinally in the under surface of the head. The head 6 is movably retained to the strip 7 by means of screws 10, which pass loosely through vertical apertures in said strip and horn and have their headed ends operating in pockets 10^a in the horn, as shown in Fig. 5, and is yieldingly supported above the spacing strip 7, due to the mounting of a plurality of coiled compression-springs 11 within pockets 11^a in said strip, the upper ends of which coact with the under side of the head 6, as shown in Fig. 5.

Within a suitable groove provided longitudinally in the surface of the horn 4 at one side of the strip 7 is mounted a female edge-folding die 12, which is shown in the drawings as comprising two flush parallel die-plates, the upper inner edge of the outer of which is beveled, as shown, to form a longitudinal recess in the surface of the die, one wall of which is tapered. This die is set at a slight angle to the plane of movement of the head 6, so that the wall of the recess in oppo-

sition to the beveled wall thereof will stand at a slight incline, as shown in Figs. 2 and 4, thus causing the outer or terminal fold at the edge of the work to incline slightly outwardly, as shown at *a* in Fig. 9, to facilitate the seam - closing operation. Mounted in a groove 13, extending lengthwise of the head 6 in superimposed relation to the female die 12, is a male-die plate or blade 14, which hangs loosely from the screws 15 in the head in a manner enabling it to have a slight inward swinging movement and has its lower outer edge beveled, as shown, to adapt such surface to coact with the beveled surface of the female die 12. As the blade 14 enters the recess in the die 12 and strikes the beveled surface thereof on the downstroke of the head 6 it will be caused thereby to swing laterally within its groove, which is enlarged for that purpose, so as to automatically assume the inclination of the inner wall of said recess, thus causing the interposed work to be driven within the recess and formed in the required shape. The blade 14 is normally retained in vertical position, or at its outer limit of swinging movement, by one or more coiled compression-springs 15^a, which are mounted within pockets 15^b in the side of the head 6 and have their thrust outwardly against the inner surface of the blade, as shown in Fig. 6. The horn 4 and head 6 are also provided on the opposite side of the strip 7 with registering dies 16 and 17 for forming the folds on the opposite edge of the work to that operated on by the dies 12 and 14. The dies 16 and 17, however, are placed in reversed positions to the dies 12 and 14 to permit an interlocking of the two folded edges, as shown at *b* in Fig. 9, the female die 16 being carried by the head 6, while the male die or blade 17 is carried by the horn 4. The dies 16 and 17 are both set rigid and in the plane of movement of the head, as it is only necessary to form the terminal fold of one edge on an incline or angle to the clinching or seam-closing movement of the pressure-foot 3, by which the seam is subsequently closed. Either or both male dies, however, may be mounted loose for this purpose, if desired.

Mounted on the surface of the horn 4 intermediate each die 12 and 17 thereon and the strip 7 is an adjustable gage-bar 18. Each of these bars is carried by a set of pins or legs 19, which project downwardly therefrom into pockets 20 in the horn. These pockets are sufficiently large to enable the pins or legs 19 to have lateral adjustment therein transversely of the horn to effect a transverse adjustment of the attached bar. An adjustment of the bar 18 is effected by a turning of the adjusting-screws 21, which screws are mounted in the horn in apertures intersecting the pockets 20, with their inner ends threaded transversely through the pins

or legs 19. The screws 21 are each prevented from longitudinal movement by a plate 22, which is secured within a pocket 23 in the side of the horn by a retaining-screw 24 and coacts with a flange 21^a on the screw 21, as shown in Fig. 4. With this construction of gage it will be apparent that either a parallel or tapering adjustment thereof relative to the associated dies may be provided, so as to form a folded edge and seam which is of equal width throughout its length or gradually widens from either end thereof, as is required in certain kinds of work.

The head 6, in addition to carrying the edge-folding dies, is also adapted to act as an anvil or bed on which the interlocked edges of the work are laid to receive the thrust of the pressure-foot 3 for the purpose of closing the seam. For this purpose the upper surface of the head is suitably shaped to receive the work and is provided with a series of gage-pins 25, which align longitudinally thereof. These pins are of the disappearing type, being mounted in pockets in the head and yieldingly retained in elevated positions by coiled compression-springs 26, which are mounted in the bases of the pockets, as shown in Figs. 4 and 5. A die 27 is carried by the pressure-foot 3 in position to coact with the seam of the work placed on the head 6 when the foot is lowered and press it into the desired shape.

The operation of my invention is as follows: The edges of the blank are first placed over the opposite sides of the horn 3 in contact with the edge-folding dies carried thereby and with their edges in abutment with the gage-bars 18 thereon, which are properly adjusted to give the desired width of fold. The press is then thrown into operation to effect a downstroke of the pressure-foot 3 and a consequent coacting of the dies of each set to form the edge folds in the interposed work. As the swinging male die or blade 14 descends upon the work it is caused to automatically adjust itself to the incline of the recess in the female die 12, thus forming the edge fold of the work at that side at an angle to the direction of movement of the die-carrying head 6, as shown at *a* in Fig. 9. After the edge folds are formed they are locked together in the manner shown at *b* in Fig. 9 and placed over the head 6 with the point of the lower or inner fold abutting the gage-pins 25, thus properly positioning the seam to receive the closing or finishing thrust of the pressure-foot 3, which is then operated for that purpose. As the folds are crushed against the head the gage-pins 25 disappear within their receiving-pockets and the seam *c* in Fig. 9 is formed.

In Fig. 8 is illustrated a modified form of the attachment in which the edge-folding parts are carried by the pressure-foot of the press-plunger or slide. In this construction

28 indicates the pressure-foot, which is adapted to be bolted to the press-plunger or slide; 29, a die-plate which is secured to the under surface of the pressure-foot and carries the swinging male die 30 and fixed female die 31; 32, a second die-plate or bar which is yieldingly spaced from the plate 29 by the strip 33 and interposed compression-springs (not shown) and carries the dies 34 for coacting with the dies 30 and 31 on the plate 29, and 35 a horn with which the base of the plate 32 coacts to close the seam of the work.

The operation of this construction is substantially the same as that of the other construction, except that the reversal of the position of the parts requires that the edges of the blank be first placed between the die-plate 29, carried by the pressure-foot 28, and the yieldingly-associated die-plate 32 for the purpose of being folded and then placed in interlocked position over the horn 35 to receive the seam-closing thrust of the under side of the die-plate or bar 32.

Having thus described my invention, what I claim as new, and desire to secure by Letters Patent, is—

1. In combination, two relatively movable parts, edge-folding dies carried by said parts, and a gage member carried by one of said parts and mounted for horizontal angular adjustment relative to the die on said part.

2. In combination, two relatively movable parts, edge-folding dies carried by said parts and one part having pockets formed therein, a gage-bar adjustably mounted on the part having the pockets and having portions projecting freely within the pockets, and means coöperating with the portions of the bar projecting within the pockets and with the pocket part for effecting an adjustment of the bar.

3. The combination with one of the die-carrying parts of an edge-folding apparatus, said part having pockets therein, of a gage-bar adjustably mounted thereon and having legs projecting within the pockets for lateral movement therein, adjusting-screws carried by said part and having their inner ends threaded transversely to the legs whereby to cause a lateral adjustment of the gage-bar when turned.

4. In combination, a die-carrying part, a head yieldingly spaced therefrom, edge-folding dies carried in registering relation by said part and head, a portion of said dies being mounted to have lateral swinging movement relative to the carrying part whereby it may assume a position at an angle to the plane of movement of the head, means for normally retaining the swinging dies in one position relative to the carrying part, and means for applying a compressing force to the head. 55

5. In combination, a horn, a head yieldingly spaced therefrom, work-gaging bars adjustably carried by the horn, edge-folding dies carried in registering relation by the horn and head, the female die having its recess disposed at a slight angle to the plane of movement of the head and the male die being mounted to have a movement relative to its carrying part, whereby it is enabled to automatically adjust itself to the incline of the female recess, and means for applying force to the head. 70

6. In combination, a die-carrying part, a normally spaced head yieldingly carried thereby, a male and a female edge-folding die carried by the head, registering male and female dies carried by the die-carrying part, an adjustable gage-bar for each set of co- 80 operating dies, and means for applying force to the head. 75

7. The combination with one of the die carrying parts of an edge-folding apparatus, of a gage-bar movably carried thereby, and screws coöperating with the bar and part for effecting an adjustment of the bar when turned. 85

8. In combination, a pressure-foot, a horn, a member disposed between said parts and yieldingly carried by one, coöperating edge-folding dies carried by said member and the part by which it is yieldingly carried, and coöperating seam-closing surfaces provided on said member and the other of said parts. 95

In testimony whereof I have hereunto signed my name to this specification in the presence of two subscribing witnesses.

JEREMIAH BINGHAM.
